(54) **SAW MILL, DOG GAUGE**

(76) Inventor: **Martin Rich**

Marlin & Rich, Caroline, N. York.
Letters Patent

The Schedule referred to in these Letters Patent and making part of the same containing a description in the words of the said Marlin & Rich himself of his improvement on iron dogs for a Saw Mill called the gauge Saw Mill dog.

To all to whom these presents shall come. Be it known that at Martin Rich of the Town of Caroline in the County of Tompkins and State of New York have invented a new and useful improvement in iron dogs for a Saw Mill called the gauge dog, saw Mill and that the following is a full and exact description of the construction and operation of said machine as invented or improved by me. First. Two cast iron plates two feet long, six inches wide placed upon the head and tail blocks of the saw Mill six inches apart and confined with iron bolts or spikes. Three eyes placed or cast upon the top of each plate, one at each end of the plate and the third in the middle from one end. On the centre of the plates a piece of cast Iron is cast or bolted two inches high on which to fasten the spring. Holes are drilled through the eyes to the half bolts. Two half bolts made of wrought or cast iron two feet long and eight inches high are fastened by quadeons four inches long to the eyes. The quadeons are cast with the half bolts and turned so as to exactly fit the holes in the eyes and are attached to the half bolts in one of the half bolts is three teeth placed in manner following, two of the teeth upon the inside from two to four inches apart and one tooth in the middle of the two teeth placed horizontally so as to keep the log down firm to the head block. On the other half bolt there is but one tooth eight inches long, the inside part of which is driven into the log to keep it firm and the outside operates as a gauge to gauge the board to any given thickness that the sawyer may desire and the log is made of cast iron eight inches wide long 4.1 feet.

at the end of each half bail running through both eyes so as to come against the end of the half bail to regulate the thickness of the board to be used, & a spring made of cast steel wire makes long fastened upon one of cast or wrought iron on the middle of the plate containing the half bail with these teeth and fingers upon the ends of the half bail so as to throw it back against the end of the nail before the half bail is driven into the end of the log. Thus by its pressure against the half bail prevents it being forced too far and making the danger to make the board of equal thickness without any stub hole. If preferred by the user the spring can be removed and the half bail guaranteed by the screw alone. If preferred square blocks of cast iron can be substituted for the screw at each end of the half bail and thus regulate the thickness of the board. In testimony whereof I have caused set my hand and signed the twenty first day of February 1835.
